(57) **CLAIM**

The ornamental design for a broom, as shown and described.

DESCRIPTION

FIG. 1 is a perspective view of a broom in accordance with the present invention;

FIG. 2 is a side elevational view, the opposite side view being a mirror image thereof;

FIG. 3 is a top plan view thereof;

FIG. 4 is a front elevational view thereof; and,

FIG. 5 is a rear elevational view thereof.

The broken lines represent bristles and a broom handle, which do not form part of the claimed design.
